UNITED STATES PATENT OFFICE.

JESSE T. SPAULDING, OF PORT BYRON, NEW YORK.

RAILROAD-TIE.

No. 901,845.

Specification of Letters Patent.

Patented Oct. 20, 1908.

Application filed September 13, 1907. Serial No. 392,731.

To all whom it may concern:

Be it known that I, JESSE T. SPAULDING, a citizen of the United States, residing at Port Byron, in the county of Cayuga and State of New York, have invented new and useful Improvements in Railroad-Ties, of which the following is a specification.

This invention relates to railroad ties, and it has for its object to provide a composite metallic and wooden tie in which a metallic casing is combined with blocks of wood that will serve to directly support the rails; said wooden blocks being readily removable so as to enable them to be exchanged for new ones after they have been rendered useless by wear or decay.

Further objects of the invention are to simplify and improve the construction and operation of this class of devices and to provide a tie which will be eminently safe, durable, and practically efficient.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a side elevation of a railroad tie constructed in accordance with the invention. Fig. 2 is a top plan view of the same. Fig. 3 is a longitudinal sectional view. Fig. 4 is an end view. Fig. 5 is a transverse sectional view taken on the plane indicated by the line 5—5 in Fig. 2.

Corresponding parts in the several figures are denoted by like characters of reference.

The casing of the improved railroad tie is made of sheet metal or plate metal, preferably steel, said plate being preferably about one half inch in thickness. A suitable blank is cut or stamped from the sheet or plate, said blank being bent to form a box-like shell or casing including the bottom 1, side walls 2—2 and end walls 3—3, the latter being formed by flaps which are overlapped and connected together by fastening means

such as rivets 4. The side walls 2—2 are provided adjacent to the ends of the casing with flanges 5—5 extending inwardly over the casing; the flanged portions of the side walls are provided with notches 6 which extend into the side walls from the upper edges of the latter for a purpose which will presently be made apparent.

Rail supporting blocks 7 which are made of wood, and which are made of a cross-sectional area, approximately corresponding to that of the standard railroad tie ordinarily employed, are fitted in the ends of the tie casing; said blocks being of a length which will enable them to be introduced between the side walls of the casing intermediate the flanged ends of said side walls, after which they may be slid or moved lengthwise within the casing to the ends of the latter where they abut upon the end walls 3; said blocks being secured in position against upward displacement by the flanges 5 and against endwise displacement by means of bolts 8 extending transversely through said blocks and through apertures formed for their reception in the side walls of the casing. The central portion of the casing is preferably pressed downward to form a depressed portion 9 which is provided with apertures 10 through which water that enters the tie casing may drain out.

The rails, one of which has been shown at 11, are supported upon the blocks 7, said rails being disposed in the notches 6 which, as hereinbefore stated, are cut of such a depth that the metallic portion of the casing will not contact with the rail flanges, the latter being supported exclusively upon the wooden blocks which possess the requisites of elasticity and resiliency to the desired degree, and which for well known reasons form rail supports that are more efficient and desirable than the comparatively unyielding metal of the casing. The rails may be secured upon the blocks, in the customary manner, by means of spikes 12; and the rail may thus be readily detached and renewed in the customary manner without involving the necessity of tools or specially skilled labor other than that which is usually employed in the construction and repairs of railroads.

The improved railroad ties may be placed in position in the customary manner, and the roadbed may be ballasted and tamped as usual. A filling of sand, gravel, dirt, cement or other suitable material may, if de-

sired, be introduced into the casing between the blocks 7; but this is entirely optional with those using the improved tie.

Having thus fully described the invention, 5 what is claimed as new is:—

In a railroad tie, a metallic casing having side walls provided with inwardly extending flanges adjacent the ends of the casing, the bottom of the intermediate portion of 10 the casing inclining downwardly toward the

center of the casing to form a depression, said bottom being formed with openings in the depression portion.

In testimony whereof I affix my signature in presence of two witnesses.

JESSE T. SPAULDING.
